SLUG CASTING MACHINE

Anthony J. Stouges, Queens Village, N. Y., assignor to Mergenthaler Linotype Company, a corporation of New York

Application June 17, 1935, Serial No. 26,911

19 Claims. (Cl. 199—47)

This invention relates to typographical slug casting machines of the general organization represented in U. S. Letters Patent No. 436,582 to O. Mergenthaler, wherein a composed line of 5 matrices is presented momentarily to one face of a slotted mold, a metal pot brought against the opposite face of the mold, and molten metal injected by a pump from the metal pot into the mold slot or cavity to form a type bar or slug 10 against the line of matrices.

In these machines, the molten metal is introduced into the mold by means of a spring actuated pump piston or plunger arranged within the melting pot and controlled in its action by a 15 rotary cam which, as well known, makes one complete rotation for each cycle of operation of the machine. The cam is so shaped as normally to maintain the pump plunger in a raised position out of action, but at one point in its circumference it is formed with a depression which, at the proper time, permits the plunger to descend more or less gradually and uniformly under the influence of its actuating spring to fill the mold 20 with molten metal for the casting operation. 25 This old arrangement is entirely satisfactory and efficient for the production of slugs of ordinary sizes, say up to 18 pt. or thereabouts, but it has not been found to be so satisfactory or efficient in machines of more recent development which 30 provide for the production of slugs of much larger sizes extending up to 60 pt. and above. For instance, in casting slugs of these larger sizes, it frequently happens that because of imperfections many of the slugs must be recast one or more 35 times before one is produced which is at all suitable for use; in fact, it is seldom attempted to make use of such slugs for high grade work or when great pressure is exerted on the slugs in taking an impression therefrom. The difficulty 40 may be explained partly by the fact that the pump plunger fails to exert sufficient pressure upon the molten metal to drive it with the requisite force and at a sufficient rate of flow into the mold and matrix cavities. Indeed, near the 45 completion of the casting operation the load applied to the plunger (which should be at its maximum) is at its minimum due to the lost tension or relaxation of the actuating spring at that time.

50 In order to overcome the foregoing difficulty, it has been proposed to provide two springs for actuating a single plunger pump with means for rendering one or both of the springs operative as desired; or to provide an arrangement where- 55 by the tension of a single spring or the leverage

through which it acts may be varied; or to connect one end of a single spring to a movable anchorage so that the original high tension of the spring may be maintained throughout the metal injecting operation; or to provide a pump comprising two plungers actuated each by an individual spring with means for rendering one or both of the plungers operative at will. In each such instance, however, the mechanism has had to be manually controlled to condition it for the desired mode of operation, and thus the operator has been burdened with the duty of effecting the proper conditioning of the machine.

According to the present invention, automatic means are employed to alter the operation of the pump by a change in the size of mold slot. While applicable to any one of the known mechanisms above referred to, the invention is herein shown as applied to the first mentioned arrangement wherein two springs are provided for actuating a single pump plunger, one spring being adapted to operate alone when casting with the smaller size molds, and both springs being operative simultaneously to actuate the plunger under greater pressure for casting with the larger size 25 molds. In controlling the automatic operation of the springs, one is permitted to be active at all times in the usual manner, and a movable stop is provided normally to hold the second spring against operation but which is moved from 30 active position automatically when a large size mold is brought into casting position so as to allow the second spring to become effective.

In carrying out the invention, an improved mounting for the pump plunger and actuating 35 spring levers is provided, which mounting is adapted to distribute the increased pressure created by the use of the two springs to different parts of the fixed machine frame, and also to permit the arrangement of the springs so that the torque effect of one on the support tends to equalize that of the other during their conjoint 40 operation. Briefly, the support comprises a bracket for supporting the plunger lever which is fixed at one end to a central vertical member of the machine frame, as usual, but has its opposite end extended and fixed to a horizontal side member of the machine frame. One spring is located, as usual, a certain distance to the right of the plunger lever, while the second or additional 45 spring is located at substantially an equal distance to the left of the lever.

In the accompanying drawings, the invention has been shown merely in preferred form and by way of example and as applied to the machine of 55

the class stated, but obviously many changes and variations may be made therein and in its mode of adaptation, which will still be comprised within its spirit. It is to be understood, therefore, 5 that the invention is not limited to any specific form or embodiment except insofar as such limitations are specified in the appended claims.

Referring to the drawings:

Fig. 1 is a side elevation, partly in section, of a 10 portion of a slug casting machine embodying the invention;

Fig. 2 is a plan view of the parts shown in Fig. 1;

Fig. 3 is an enlarged front elevation of the parts 15 shown in Fig. 1, except that the showing of the first elevator is omitted and some of the parts are broken away;

Fig. 4 is a plan view of the mold disc and adjacent parts shown in Fig. 3;

20 Fig. 5 is a view similar to Fig. 3, partly broken away, but with some of the parts occupying different positions; and

Fig. 6 is a vertical section taken on the line 6—6 of Fig. 5.

25 As shown in Fig. 3, the mold disc A is equipped as usual with four molds A¹, A¹, A², A², any one of which may be brought into use by adjusting the disc manually about its axis through the medium of the driving pinion A³. The molds A¹ are 30 representative of the plain unrecessed variety used for casting slugs of from 5½ pt. to 10 pt. body size, whereas the molds A² are representative of the larger head-letter or recessed variety which are used mainly in casting display slugs 35 ranging in size say from 36 pt. to 60 pt. The disc A is carried as usual by the mold slide A⁴ arranged to impart a fore-and-aft movement thereto for effecting the lockup of the mold with a line of matrices preparatory to the casting 40 operation and which has fixed to it a bracket A⁵ carrying guide shoes (not shown) tracking on the front and rear faces of the disc A to insure its true running when rotated about its axis.

In Fig. 1, the parts are shown in the relative 45 positions they occupy just prior to the commencement of the casting operation. In this condition of the parts, the slotted mold A², carried by the rotary disc A, is closed at the front by the composed line of matrices X presented momentarily 50 thereto by the vertically movable first elevator B, and it is closed at the rear by the mouthpiece C¹ of the melting pot C sustained within the rocking frame or jacket D. The pot C, which contains 55 a supply of type metal maintained in a molten condition by means of a suitable burner (not shown) is formed with a throat or passage C² through which the molten metal is forced into the mold during the casting operation.

The plunger E is connected by means of a rod 60 or link E² to the free end of a vertically movable lever E³, which latter is formed at its opposite end with a bearing sleeve E⁴ mounted loosely on a fixed transverse rod E⁵ arranged in a bracket F fixed to a central vertical member G of the 65 machine frame, as by bolts F¹. The sleeve E⁴ is provided with two arms E⁶ and E⁷, the former carrying a roller E⁸ which is arranged to track upon the periphery of the usual rotary cam E⁹ fast to the main shaft E¹⁰ of the machine, and the latter being extended laterally beneath a further lever E¹¹ which is also mounted loosely on the fixed rod E⁵ to the right of the vertical frame member G and has its free end connected to a tension spring E¹² pulling downwardly thereon from a fixed part of the machine. As well under-

stood, the peripheral face of the cam E⁹ is concentric throughout except at one portion of its circumference, where it is cut away or formed with a depression to provide the customary sloping surfaces E¹⁴ and E¹⁵. When the machine is 5 at rest, the roller E⁸ is in contact with the concentric portion of the cam E⁹, so that the plunger E is maintained in its raised or inoperative position, as indicated in Fig. 1. This condition obtains until the metal injecting period arrives, 10 when the cam (rotating in the direction of the arrow) brings its sloping surface E¹⁵ into engagement with the roller E⁸, which then descends along such surface to the bottom of the depression, thus permitting the spring E¹², through the 15 connections described, to depress the plunger E and force a charge of molten metal into the mold. As the cam continues to rotate, the roller E⁸ is engaged sooner or later by the sloping surface E¹⁴ and the parts thereby restored to and maintained 20 in their original condition to await the next casting operation.

So far as described, the parts, their construction, and mode of operation, except as herein-after pointed out, are or may be the same as 25 those embodied in the standard commercial machine and in themselves constitute no part of the present invention.

According to the invention, the bracket F is 30 extended, as at F², toward the left side of the machine (Fig. 3) and formed at its extreme end with a depending arm F³, which is securely fastened at its lower end to the horizontal side member G¹ of the fixed machine frame. A second depending arm F⁴ is formed on the bracket extension F² in parallel with and spaced inwardly from the arm F³, and each arm is formed with a hole f in which a rod E¹⁶ is fixed. A lever E¹⁷ is pivotally mounted on the rod E¹⁶ and has its free end connected by a rod E¹⁸ to a tension spring E¹⁹ pulling 35 downwardly thereon from a fixed part of the machine, the lever E¹⁷ being arranged to the left of the plunger lever E³ a distance substantially equal to that between the lever E³ and the spring lever E¹¹. The plunger lever E³ is formed about mid-45 way of its length with an arm E²⁰, extending to the left beneath and in supporting engagement with the spring lever E¹⁷ and being bent to have its free end pivoted to the rod E¹⁶. It is through the arm E²⁰, by its supporting engagement with the lever E¹⁷, that the spring E¹⁹ is held tensioned by the cam E⁹ and also transmits its force in 50 actuating the plunger lever E³.

The depending arms F³ and F⁴ of the bracket F are formed below the rod E¹⁶ with recesses or 55 guideways, such as F⁷ shown in the arm F⁴ in Fig. 6, in which there is arranged a slide stop H removably held in the guideways by cover plates F⁸ and F⁹, respectively. The stop H is normally held in its leftmost position by a tension spring H¹, having one end attached to a pin H² on the stop H and the other end secured to an eyelet H³ fixed to the bracket arm F³, and is movable horizontally against the tension of spring H¹ to carry a raised portion H⁴ thereon 60 out of the path of a lug E²¹ formed on the underside of the spring lever E¹⁷ (Fig. 6). Thus, by reciprocating the stop H, the spring E¹⁹ can be rendered active or inactive, as desired, it being rendered active when the stop H is moved to its 65 rightmost position with the raised portion H⁴ clear of the lug E²¹ at which time the spring is free to act conjointly with the spring E¹² during the metal injecting period under the control of the cam E⁹.

For the purpose of setting the stop H automatically, the mold disc A is equipped with a block or shoe J fixed, as by screws J¹, adjacent the leading end of each of the large size molds 5 A². Each block J is formed with two cam surfaces J² and J³, and an intermediate surface J⁴ concentric with the axis of the disc A. When a large mold A² is brought into casting position, as shown in Fig. 3, the cam surface J² acts through 10 a bell-crank lever K to operate a train of connections and move the stop H to its spring releasing position, the surface J⁴ acting to hold the stop in this condition until the lever E¹⁷ has been raised by the cam E⁹ following the metal 15 injecting operation, and the cam surface J³ thereafter allowing the stop to return to its normal spring locking position under the influence of the actuating spring H¹. The cam surface J³ also serves to prevent interference on the part 20 of the bell-crank lever K in the event that the disc A is rotated in a clockwise direction during the selection of a mold.

The train of connections for operating the stop H comprises a horizontally disposed rock shaft 25 K¹ (Figs. 1, 3 and 5) journaled near its opposite ends in bearings K² and K³ secured to the side member G¹ of the machine frame. At the rear, the shaft K¹ carries an upstanding lever K⁴ whose bifurcated free end K⁵ receives a pin H⁵ 30 projecting from the stop H, while at the front the shaft has fixed to it a lever arm K⁶ arranged substantially at right angles to the lever arm K⁴, the free end of the arm K⁶ being formed with a flattened upper surface K⁷ located beneath and in engagement with the free end of one arm K⁸ of the bell-crank lever K before referred to. The bell-crank lever K is pivotally mounted on a stud K⁹ secured to a bracket K¹⁰ fixed to the 35 guide shoe bracket A⁵ for the mold disc A, as by screws K¹¹, and the distal ends of its arms K⁸ and K¹² are formed each with a rounded boss K¹³ which provides an engaging surface to co-operate with the lever K⁶ and the blocks J. A pin K¹⁵, arranged in a fixed part of the machine 40 for engagement with the arm K⁸ of the bell-crank lever K, is provided as a stop to resist the pull of the spring H¹ and maintain the parts normally in the position shown in Fig. 5.

In operation, when the mold disc A is rotated 45 to bring one of the large molds A² into casting position, the cam surface J² of the block J is brought into engagement with the free end of the arm K¹² of the bell-crank lever K, just before the disc A comes to rest, and rocks the lever K about its stud K⁹ to the position shown in Fig. 3. This rocking of the bell-crank lever acts through 50 the lever arm K⁶ to rock the shaft K¹ in a clockwise direction, moving the lever arm K⁴ and stop H to the right against the pull of the spring H¹ to carry the raised portion H⁴ out of the path of the lug E²¹ on the spring lever E¹⁷. In this condition of the parts (see Fig. 3), when the roller E⁸ tracking on the cam E⁹ rides down the inclined surface E¹⁶ of the cam, the spring E¹² acts, as 55 usual, to rock the plunger lever E³, but now the spring E¹⁹, acting at the same time through the lever E¹⁷ and arm E²⁰, supplements the action of the spring E¹² and thus causes the plunger E to inject metal into the mold more rapidly and under greater pressure than if the spring E¹² were 60 acting alone, as for a small mold. When one of the small molds A¹ (which are without the blocks J) is brought into casting position, the stop H is allowed to remain in its normal locking 65 position as shown in Fig. 5 and hence only the

spring E¹² is allowed to act during the metal injecting operation.

By mounting the bracket F on the vertical frame member G and its extended portion F² on the horizontal side member G¹, the bracket is rigidly supported against twisting, and when the spring E¹² acts either alone or conjointly with the spring E¹⁹, the spring pressure is distributed to different parts of the machine frame. Moreover, the arrangement of the springs E¹² and E¹⁹ at substantially equal distances on opposite sides of the plunger lever E³ causes the pull of one to offset or balance the torque effect of the other on the bracket F. Hence, the spring arrangement and the bracket anchorage both act to produce a more even running of the roller E⁸ on the cam E⁹ and so prevent uneven wear of the latter. 10

It should be noted that although the mold disc A partakes of a fore-and-aft movement before and after the casting operation, this movement 15 is permitted by the free engagement of the arm K⁸ of the bell-crank K (which is movable with the disc) with the wide flattened upper surface K⁷ of the relatively stationary lever arm K⁶ (see Fig. 4). Furthermore, although the disc A partakes of a full counter-clockwise rotation during each casting operation, so that the bell-crank lever K is engaged and actuated twice when two molds A², as herein, are mounted on the disc, one of those operations will be entirely idle, since, 20 through the arms E⁷ and E²⁰, the roller E⁸ tracking on the cam E⁹ maintains both spring levers E¹¹ and E¹⁷, in their uppermost position and restrains the action of the springs E¹² and E¹⁹ at 25 all times except during the metal injecting period, 30 at which time, of course, the disc A remains stationary.

As already stated, the invention has been shown merely by way of example and in preferred form and as applied to a standard machine of the class 35 stated. It is to be understood, however, that there are different forms of the machine, as well as different forms of pump mechanisms, to which the invention is equally well adaptable. Hence, in its broader aspects, the invention is directed 40 to the automatic conditioning of the pump to operate under different amounts of pressure for injecting metal into molds of different sizes according to the size of the mold employed at the time, as well as to the distribution of such pressure 45 to different parts of the machine frame.

Having thus described my invention what I claim is:

1. In a slug casting machine, the combination 55 of a metal pot, a pump for forcibly injecting molten metal from the metal pot into a mold, means for operating the pump, means for conditioning the pump to vary its operative effect in injecting the metal into the mold, and means controlled by a change of mold size for automatically conditioning the pump to correspond.

2. In a slug casting machine, the combination 60 of a metal pot, a pump for forcibly injecting molten metal from the metal pot into a mold, means for operating the pump, means for conditioning the pump to cause it to act under different amounts of pressure, and means controlled by a change of mold size for automatically conditioning the pump to correspond.

3. A combination as in claim 2 characterized 65 by the fact that the automatic conditioning of the pump is dependent upon a change of molds.

4. A combination as in claim 2 characterized 70 by the fact that the automatic conditioning of 75

the pump is controlled by means associated with the mold employed.

5. In a slug casting machine equipped with a plurality of molds for casting slugs of different sizes and any selected one of which may be brought into use as desired, the combination of a metal pot, a pump for forcibly injecting molten metal from the metal pot into the selected mold, means for operating the pump, means for conditioning the pump to vary its operative effect in injecting the metal into the mold, and automatic means controlled by the selected mold for effecting the conditioning of the pump to correspond.

15. 6. In a slug casting machine equipped with a plurality of molds for casting slugs of different sizes and any selected one of which may be brought into use as desired, the combination of a metal pot, a pump for forcibly injecting molten metal from the metal pot into the selected mold, means for operating the pump, means for conditioning the pump to vary its operative effect in injecting the metal into the mold, and means actuated by a change of molds for controlling said conditioning means.

30. 7. In a slug casting machine equipped with a plurality of molds for casting slugs of different sizes and any selected one of which may be brought into use as desired, the combination of a metal pot, a pump for forcibly injecting molten metal from the metal pot into the selected mold, means for actuating the pump, means for conditioning the pump to cause it to act under different amounts of pressure for molds of different sizes, and automatic means controlled by the selected mold to condition the pump to correspond.

40. 8. A combination as in claim 7, wherein a plurality of springs are employed for actuating the pump, and wherein one at least of the springs is selectively rendered active or inactive by said automatic conditioning means.

45. 9. In a slug casting machine equipped with a plurality of molds for casting slugs of different sizes and any selected one of which may be brought into use as desired, the combination of a metal pot, a pump for forcibly injecting molten metal from the metal pot into the selected mold, means for actuating the pump, the pump being operable under different amounts of pressure for molds of different sizes, and means governed by the selected mold for automatically controlling the amount of pump pressure to correspond.

55. 10. In a slug casting machine equipped with a plurality of molds for casting slugs of different sizes and any selected one of which may be brought into use as desired, the combination of a metal pot, a pump for forcibly injecting molten metal from the metal pot into the selected mold, a pair of springs for actuating the pump, a movable member associated with one of said springs and acting normally to render it inactive, and means associated with large size molds to actuate said member to render the spring active.

70. 11. In a slug casting machine equipped with a plurality of molds for casting slugs of different sizes and any selected one of which may be brought into use as desired, the combination of a metal pot, a pump for forcibly injecting molten metal from the metal pot into the selected mold, a pair of springs for actuating the pump, and means for rendering one or both of

said springs active according to the mold selected.

12. In a slug casting machine, the combination of a mold disc equipped with a plurality of molds for casting slugs of different sizes and 5 adjustable to select one or another of the molds as desired, a metal pot, a pump for forcibly injecting molten metal from the metal pot into the selected mold, a pair of springs for actuating the pump, and means actuated by the adjustment of the mold disc for causing one or both of said springs to act when the selected mold is brought into casting position.

13. In a slug casting machine, the combination of a mold disc equipped with a plurality of molds for casting slugs of different sizes and 15 adjustable to select one or another of the molds as desired, a metal pot, a pump for forcibly injecting molten metal from the metal pot into the selected mold, a pair of springs for actuating the pump, a movable member associated with one of the springs and acting normally to render it inactive, and means operative according to the adjustment of the mold disc to actuate said member to render the spring active when the 20 selected mold is brought into casting position.

14. In a slug casting machine, the combination of a mold disc equipped with a plurality of molds for casting slugs of different sizes and adjustable to select one or another of the molds 30 as desired, a metal pot, a pump for forcibly injecting molten metal from the metal pot into the selected mold, a pair of springs for actuating the pump, a movable member associated with one of the springs and acting normally to render it 35 inactive, and means carried by the mold disc for causing said member to be actuated to render the spring active when the disc is rotated to bring the selected mold into casting position.

15. In a slug casting machine, the combination of a fixed machine frame including a centrally located member and a side member, a metal pot located between said members, a pump for forcibly injecting molten metal from the metal pot into a mold, said pump including a plunger 45 and a spring actuated lever for operating the plunger, and supporting means in which said plunger lever is pivotally mounted, said supporting means being secured to the central frame member and to the side frame member to distribute 50 the spring pressure exerted on the plunger operating lever equally to both said frame members.

16. In a slug casting machine, the combination of a fixed machine frame including a centrally located member and a side member, a metal pot located between said members, a pump for forcibly injecting molten metal from the metal pot into a mold, said pump including a plunger and an actuating lever therefor, spring means 60 acting through a second lever to operate the plunger, a bracket in which said plunger lever is pivotally mounted, said bracket being secured at one end to the vertical frame member and at the other end to the horizontal frame member 65 to distribute the spring pressure exerted on the plunger operating lever equally to both said frame members, and a supporting rod mounted in said bracket and on which both the spring and plunger levers are mounted.

70. 17. In a slug casting machine equipped with a plurality of selectable molds for casting slugs of different sizes, the combination of a fixed machine frame including a vertical central member and a horizontal side member, a metal pot 75

- arranged between said members, a pump plunger for forcibly injecting molten metal from the metal pot into the selected mold for casting, said plunger being carried by a lever, a bracket fixed at 5 one end to the vertical member and at the other end to the side member of the frame, a pair of springs located one on each side of the metal pot for actuating said plunger, and an actuating lever connected with each spring, said plunger 10 and spring levers all being pivotally mounted in said bracket and the spring levers being located equidistantly from the plunger lever on opposite sides thereof.
18. In a slug casting machine equipped with 15 a plurality of selectable molds for casting slugs of different sizes, the combination of a fixed machine frame including a vertical central member and a horizontal side member, a metal pot arranged between said members, a pump plunger 20 for forcibly injecting molten metal from the metal pot into the selected mold for casting, said plunger being carried by a lever, a bracket fixed at one end to the vertical member and at the other end to the side member of the frame, a 25 pair of springs located one on each side of the metal pot for actuating said plunger, an actuating lever connected with each spring, said plunger and spring levers all being pivotally mounted in said bracket and the spring levers being located equidistantly from the plunger lever on opposite sides thereof, and an offset arm con-
- nected with the plunger lever and pivotally mounted at its free end in said bracket, said arm extending in the path of one of said spring levers for operative engagement therewith.
19. In a slug casting machine equipped with a 5 plurality of selectable molds of different sizes carried by a mold wheel rotatable to bring a selected mold into casting position, the combination of a fixed machine frame including a vertical central member and a horizontal side member, 10 a metal pot located between said frame members, a pump including a plunger carried by a lever pivotally mounted in a bracket secured at one end to the vertical frame member and at the other end to the side frame member, said 15 plunger being adapted for forcibly injecting molten metal from the metal pot into the selected mold for casting, a pair of springs connected to the pump lever for actuating the pump plunger, means including a movable stop for rendering one 20 of said springs active or inactive to vary the amount of spring pressure for actuating the pump plunger according to the size of the mold selected, said means normally rendering the spring inactive, and control means carried by the mold wheel 25 and operative through a train of connections to effect the movement of the stop and render said spring active when a large size mold is brought into casting position.

30 ANTHONY J. STOUGES.
